UNITED STATES PATENT OFFICE.

BERNARD PERITZ, OF BROOKLYN, NEW YORK.

CHANGEABLE EXHIBITOR.

1,183,763.

Specification of Letters Patent. Patented May 16, 1916.

Application filed August 22, 1914. Serial No. 858,111.

To all whom it may concern:

Be it known that I, BERNARD PERITZ, a citizen of the United States, and a resident of Brooklyn, in the county of Kings and State of New York, have invented certain new and useful Improvements in Changeable Exhibitors, of which the following is a specification.

This invention relates to improvements in changeable exhibitors for the display of news items, advertising matter, pictures, etc.

The objects of this invention are to eliminate the objectionable features of this class of advertising mechanism, and to create the largest possible advertising space in comparison with the container of the mechanism and sign plates, and to present to the public an advertisement or sign which has a flat or even surface that stands vertical and is easily read.

The further objects are to provide an exhibitor of this class on which the advertisement can be used on both sides of the exhibition plates and the matter of an advertisement or picture may be displayed on two plates and exhibited at the same time, and the gap which appears between the plates of this style of exhibitor is eliminated, or in other words the two plates appear to the eyes as one.

The still further object is to provide a device of this character from which the sign can be easily and quickly removed as a whole or in part and new matter inserted when desired, so that a single advertisement or more may be changed without disturbing the others or interfering with the mechanism.

The still further objects are to provide a mechanism which can be easily and cheaply manufactured and operated without getting out of order.

It will be seen that I have accomplished the foregoing objects, by referring to the accompanying drawing forming a part of this specification, of which—

Figure 1 is a front elevation of my improved exhibitor; Fig. 2 is an end elevation partly broken away to show the retarding springs of the sign holder; Fig. 3 is a vertical section taken on the line 3—3 of Fig. 2; and Fig. 4 is a perspective view of one of the trunnions upon which the sign plate is operated and showing the retarding member.

By referring to the several views it will be seen that I have provided a suitable housing 4 the contour of which follows the outline of the travel of the edge of the sign plates 5 with the exception that at the front, 60 where the sign plates turn over, or in other words swing on their trunnions 6 and pass through a motion of one hundred and eighty degrees and present their reverse side to view; at this point the housing 4 is provided 65 with a rectangular opening 7 which allows the sign plates to swing out into space.

Located in the bearings 8' of the end walls 8 and 9 is the operating shaft 10, which is provided at one end with flattened 70 surfaces 11 so that it may be revolved with a key or crank in order to wind up the several springs 12, 13, 14, 15 and 16, which are contained in the drums 17, 18, 19, 20 and 21 respectively, which revolve loosely on the 75 shaft 10, which is prevented from rotating by the ratchet 24 and pawl 25. Pinned to the shaft 10 is a sleeve 22, to which is secured one end of the spring 12, the other end of which is secured to the periphery of 80 the drum 17, whose hub 17' extends into the drum 18, and one end of the spring 13 is secured to the hub 17' and the other end to the inner periphery of the drum 18. The other drums are connected up in like manner, the spring 14 connecting the hub 18' and drum 19, and the spring 15 the hub 19' and drum 20, and the spring 16 the hub 20' and drum 21, which in turn is secured to the revolving disk 26, which is connected to 85 the revolving disk 27 by a plurality of tie rods 28. Near the periphery of the disks 26 and 27 are a plurality of holes evenly spaced, which form bearings for the trunnions 6 of the sign plates 5. The trunnions 95 6 are provided with shoulders or bearing surfaces 6' to keep the sign plates in alignment and which are secured in the main portion 6'' of the trunnion members. The trunnions 6 have their ends slotted at ninety 100 degrees to the trunnion main portion, and in these slots are secured the retarding members or plates 29, which come into contact with the springs 30, which are secured to the extensions 31 on the end walls 8 and 9. The springs 30 are for absorbing the shock caused by the momentum when the sign plates turn over; and if not retarded each plate in falling would strike with much force against the preceding one. The 105

springs 30 are provided with tension bolts 32 to increase or decrease the strain on the plates, 29, and the bolts are adjusted through the openings 33 in the end walls.

5 Secured to the end wall 9 is a segmental shaped member 34 made of suitable material, which acts as a friction brake, and more or less tension may be exerted against the disk 26 by regulating the hand screw 35
10 which bears against the brake 34, and by so doing the speed of the travel of the signs can be regulated as desired.

In a suitable bearing in the end wall 9 is a plunger which can be shoved into any of 15 the holes 37 in the disk 26 to prevent the signs from operating whenever desired, or when it is necessary to change the display.

It will be noted that I secure the sign plate to the trunnions 6 so that when two 20 signs are being exhibited the edges of the two signs come in contact with each other, as clearly shown in Figs. 1 and 2; that is to say, when the face 5' of the upper sign is exhibited the lower edge 5'' of the sign plate 25 5 touches the upper edge 5'' of the lower sign plate 5 when the face 5''' is exhibited. The sign plates 5 are provided with small clips 39 around their edges which extend on both sides of the plates, and under these 30 clips are inserted the advertising cards, which have been first cut in two so that two plates carry one sign or advertisement, or each of a pair of plates carry a half of one sign on their adjacent faces.

35 The operation is very simple. By revolving the shaft 10 the spring 12 will be wound up, and when tight it will cause the spring 13 in its turn to be wound up, and so on until all of the springs are wound tight on the shaft 10, 40 which is held from turning or unwinding by the ratchet 24. The stud 36 is then withdrawn, which allows the disks 26 and 27 to revolve at a speed which is regulated by the friction brake 34. The revolving of the 45 disks 26 and 27 carries the sign plates around with them and causes the sign plates to assume the position shown in Fig. 2, and it will be seen that the two plates which are being exhibited stand perfectly vertical and 50 have a slow downward travel, which is regulated by the length of the members 40. As will be seen, when the upper edge of the sign plate passes below the end of the members 40 its weight above the trunnions 6 will 55 cause the sign plate to swing forward and down through the motion of a semicircle and present its opposite side to view, and in so doing the retarding members 29 of the sign swing in a semi-circle under the springs 30, 60 and upon the last part of their movement raise the springs 30 from the dotted position to the full line position shown in Fig. 2, and thus the retarding strain gradually in-

creases and reaches its maximum resistance on the last part of the movement of the 65 sign. The continuous movement of the disks 26 and 27 causes the next plate to be in position as the previous plate turns, and this movement of the disks also causes the retarding members to gradually leave the 70 springs 30 and allow them to resume the dotted position before the next plate is ready to turn on its trunnions. When it is desired to stop the sign, all that is necessary is to insert the stud 36 in any of the holes 75 37, and if it is necessary to change a sign the old sign can be taken out and a new one slipped in under the clips 39.

Having fully described my invention, what I desire to claim is:

80

1. An exhibiting device consisting of a shaft, a pair of disks on the shaft, a set of sign plates, a pair of trunnions for each plate consisting of a slotted bar engaging the plate and a journal projecting from each 85 bar, clips on the plates for removably securing cards on the plates, the trunnions being swung between the disks in a circular series, an arm extending radially from one trunnion of each plate, and a spring strip 90 arranged to engage each said arm to retard the momentum of the plate as swung to reversed exhibiting position.

2. An exhibiting device consisting of shaft, a pair of disks on the shaft, a set of 95 sign plates each having a pair of trunnions, the trunnions being swung in the disks respectively in a circular series, and the plates being so disposed as to be consecutively positioned in vertical alignment with adjacent 100 plates to display their opposite sides in sequence, shock absorbing means to retard the momentum as each plate is swung to exhibiting position, comprising an arm on one trunnion of each plate, and a spring strip 105 engaged by each arm as the plate swings to reversed display position.

3. An exhibiting device consisting of a driven shaft, a pair of disks carried by the shaft, a plurality of plates mounted between 110 the disks, a half sign on each adjacent plate with the sign disposed on adjacent plates, each plate having a pair of trunnions working in evenly spaced bearings in the disks, an adjustable spring, and a member on each 115 trunnion that contacts with and lifts said spring on the latter part of the turning movement of the trunnions.

Signed at New York, in the county of New York and State of New York, this 19th 120 day of August, A. D. 1914.

BERNARD PERITZ.
